UNITED STATES PATENT OFFICE.

JOHN F. O'CONNOR, OF CHICAGO, ILLINOIS, ASSIGNOR TO WILLIAM H. MINER, OF CHICAGO, ILLINOIS.

TANDEM-SPRING DRAFT-RIGGING.

1,086,553.

Specification of Letters Patent. Patented Feb. 10, 1914.

Application filed April 16, 1910. Serial No. 555,780.

To all whom it may concern:

Be it known that I, JOHN F. O'CONNOR, a citizen of the United States, residing in Chicago, in the county of Cook and State of Illinois, have invented a new and useful Improvement in Tandem-Spring Draft-Rigging, of which the following is a specification.

My invention relates to improvements in tandem spring draft rigging for railway cars.

My invention consists in the novel construction of parts and devices and in the novel combinations of parts and devices herein shown and described and more particularly specified in the claims.

In the accompanying drawing forming a part of this specification, Figure 1 is a plan view, partly in horizontal section of a tandem spring draft rigging embodying my invention. Fig. 2 is a side elevation of one side plate. Figs. 3 and 4 are vertical cross sections on lines 3-3 and 4-4 respectively, of Fig. 1. Fig. 5 is an enlarged detail perspective view showing one half of one of the side plates or stop castings which are secured to the center sills or other draft members of the car frame and against which the followers abut. Figs. 6 and 7 are detail cross sections on lines 6-6 and 7-7 respectively of Fig. 5. Fig. 8 is a detail perspective view of the vertical thimble and Figs. 9 and 10 are detail plan views illustrating the operation of the vertical thimble, followers and springs in centering the draw-bar.

In the drawing 1, 1 represent the center sills or other frame members of a car to which the draft rigging, side plates or stop castings are secured; 2 the end sill; 3 the draw-bar; 4 the draft yoke; 5, 6, 7, 8 the followers; 9, 10 tandem arranged springs, each preferably having a smaller spring 9^a, 10^a nested within it; 11 the vertical thimble or abutment block secured to the draft yoke at its middle portion and fitting between the two intermediate followers 6, 7; 12 the side plates or stop castings secured to the draft sills and against which the followers abut; and 13, 13, the carriers or tie plates removably secured to the stop castings 12 by short bolts 14.

The draft yoke 4 has on its upper and lower members or arms, gibs 15 engaging corresponding shoulders 16 on the draw-bar

which coöperate with the rivets 17 in securing the draft yoke to the draw-bar.

The vertical thimble or abutment block 11 is made of a hollow, rectangular box shape, as will be readily understood from Figs. 4 and 8 of the drawing, and it is provided at its upper and lower ends with parallel vertical shoulders or flanges 18 to receive the upper and lower limbs or members of the draft yoke, which thus serve to relieve the rivets 19 from any prying or shearing strain when the draw-bar and draft yoke swing from side to side. The vertical thimble 11 is provided with convexly curved upright faces 11^a for engagement with the adjacent upright faces or edges of the side plates or stop castings 12 to permit the draw-bar and draft yoke to swing laterally or from side to side as required when the cars are rounding curves, the vertical thimble thus serving in the nature of a fulcrum or pivot for the draw-bar and draft yoke in swinging from side to side. The vertical thimble is also provided with wide or laterally extending flat faces 20 for engagement with the intermediate followers 6, 7 and thus enable the tandem springs 9, 10, in coöperation with the vertical thimble and followers, to automatically center the draw-bar or restore it to position after it has been swung to one side about the vertical thimble as a fulcrum or pivot. This centering function of the vertical thimble 11, in connection with the followers 6, 7 and tandem springs 9, 10 will be readily understood from Figs. 9 and 10 of the drawing, the former showing the draft yoke and draw-bar centered, and the latter showing the same swung to one side and the springs under tension to center the draw-bar or restore it to its central position through the action of the laterally extended upright flat faces of the thimble 11 which engage the followers 6 and 7 at diagonally opposite corners.

As the vertical thimble 11 is of a hollow rectangular form or construction, the rivets 19 which secure the same to the upper and lower limbs of the draft yoke may be and are short rivets instead of single long rivets, heretofore customarily employed, each of which extends entirely through the vertical thimble as well as through the upper and lower limbs of the draft yoke. This improved hollow box shaped construction of the vertical thimble not only materially

lightens the weight and reduces the cost, but it also affords a much stronger and more reliable construction, as the short rivets 19 are readily caused to swell out and completely fill the holes in the draft yoke and thimble, and thus to draw and secure the parts together with absolute rigidity and without any possibility for looseness or play. This hollow construction of the thimble and 10 the use of short rivets 19 for securing the same to the draft yoke very greatly increases the shearing strength of the rivets, and the parallel shoulders 18, 18 which embrace the draft yoke on each side also 15 operate to relieve the rivets from shearing strain when the draw-bar is swung forcibly to one side.

The side plates or stop castings 12 are of malleable iron and each comprises a main 20 upright web 21 and four horizontal webs 22, 23, 24 and 25, the main upright web having transversely sunken portions 26 and 26^a and projecting or raised portions 27 and 27^a and a longitudinally sunken back portion 28 25 flush with the edges of the upper and lower horizontal webs or flanges 22 and 25 to fit against the center sill or draft member 1. The transversely sunken portions 26—26^a and projecting portions 27—27^a of the main 30 or upright web 21 are connected by upright transverse webs or shoulders 29—29^a, 30—30^a, 31—31^a, 32—32^a, 33—33^a, 34—34^a, 35—35^a, and 36—36^a constituting the front, 35 rear and intermediate main and limiting stops for the followers to abut against, the upright sunken portions 26—26^a forming the guiding surfaces for the ends of the followers. The main upright web 21 of each 40 of the side plates or stop castings 12 also has at each end inclined portions 38 and 38^a to further brace and stiffen the front and rear stop shoulders 29—29^a and 36—36^a.

Each of the side plates or stop castings 12 is also provided with upright transverse 45 connecting or bridge webs 39 extending across the longitudinal central channel 40 formed by the two intermediate horizontal webs 23, 24, and such channel in a measure separates or divides the stop casting as a 50 whole into upper and lower members, the upper member consisting of the two uppermost horizontal webs 22, 23 and the sunken and projecting portions 26, 27 of the upright web with their connecting stop shoulders, and the lower member comprising the 55 two lowermost horizontal webs 24, 25, and the sunken portions 26^a and projecting portions 27^a of the main upright web 21. The construction of the malleable iron side casting 12 thus, with the central longitudinal dividing channel 40 between its upper and lower members in connection with the upright transverse bridge or connecting webs 39 between the upper and lower members of 60 65 the integral casting materially reduces the

amount or weight of metal required, and also at the same time greatly increases the strength, efficiency and reliability of the stop casting to withstand the heavy blows to which it is subjected through the followers. The upper and lower horizontal webs 22 and 25 are connected at their ends by a shallow, transverse upright rib 41 into which the horizontal webs 22 and 25 merge by a gradual taper 42. The central, longitudinal channel 40 formed by the intermediate horizontal webs 23, 24 and back portion 28 of the main upright web 21 is provided with a series of rivet holes through which the short rivets 43 are inserted, by 70 which each of the stop castings 12 is secured to its center sill 1. The rivets 43 are thus all, excepting a pair at each end, located in the central longitudinal line of the stop casting, which is a matter of convenience and 75 economy in drilling the rivet holes and applying the stop castings to the car sills, and also brings the rivets in the central, horizontal plane of the draw-bar thrust, thus adding to the effective strength. Each of 80 the side plates or stop castings 12 is also provided with depending arms or projections 44 having slots or sockets 45 to receive the short bolts 14, and shoulders 46 to engage the heads 47 of said bolts by which the carrier straps or tie-plates 13 are secured to the stop castings 12. The carrier straps 13 are provided with flanges or shoulders 48 to engage the outer faces of the arms 44 and thus cause the carrier straps to serve also as tie- 90 plates to bind or tie together the two stop castings 12 and the center sills to which the stop castings are secured. The lower limb or member of the draft yoke 4 rests directly upon the carriers 13, thus supporting the 95 draft rigging from the stop castings 12 through the carriers 13 which are removably secured to the stop castings. This enables the draft rigging to be readily removed and replaced. 100

My improved form of stop casting 12 not only results in a material reduction in amount of metal required and cost, but it is also specially adapted to be readily molded and cast, no cores whatever being required. 115

I claim:—

1. In a tandem spring draft rigging, a draft yoke having a hollow, upright thimble secured to the draft yoke by short rivets extending through the upper and lower limbs of the draft yoke and through the upper and lower horizontal walls of the hollow thimble, said thimble having shoulders on its upper and lower faces to embrace the upper and lower limbs of the draft yoke, 120 substantially as specified.

2. In a tandem spring draft rigging, the combination with a draw-bar, draft yoke, tandem arranged springs and followers, of stop castings having front, rear, interme- 125 130 135

diate and limiting stops for the followers to abut against, and each comprising a main upright web and four horizontal webs, the main upright web having alternate sunken 5 and raised portions to form the stop shoulders, and the two intermediate horizontal webs separating the integral stop casting into upper and lower members with a central, longitudinal channel between, substantially as specified.

3. In a tandem spring draft rigging, the combination with a draw-bar, draft yoke, tandem arranged springs and followers, of stop castings having front, rear, intermediate and limiting stops for the followers to abut against, and each comprising a main upright web and four horizontal webs, the main upright web having alternate sunken 15 and raised portions to form the stop shoulders, and the two intermediate horizontal webs separating the integral stop casting into upper and lower members with a central, longitudinal channel between, and upright transverse bridge webs connecting said 20 upper and lower members, substantially as specified.

4. In a tandem spring draft rigging, a

stop casting consisting of a main upright web and four horizontal longitudinal webs, the two intermediate webs forming a central longitudinal channel, said longitudinal channel dividing the integral stop casting into upper and lower members, said upper and lower members each having alternate depressed and projecting portions to form 30 the stop shoulders, substantially as specified.

5. In a tandem spring draft rigging, a stop casting consisting of a main upright web and four horizontal longitudinal webs, the two intermediate webs forming a central 35 longitudinal channel, said longitudinal channel dividing the integral stop castings into upper and lower members, said upper and lower members each having alternate depressed and projecting portions to form the stop shoulders, said stop casting having upright transverse bridge webs extending across said longitudinal channel, substantially as specified.

JOHN F. O'CONNOR.
